UNITED STATES PATENT OFFICE

160,341

PLAYGROUND DEVICE

Alexander A. Reicher, Los Angeles, Calif.

Application October 20, 1947, Serial No. 142,015

Term of patent 14 years

(Cl. D34--5)

To all whom it may concern:

Be it known that I, Alexander A. Reicher, a citizen of the United States, residing at Los Angeles, county of Los Angeles, and State of California, have invented a new, original, and ornamental Design for a Playground Device, of which the following is a specification, reference being had to the accompanying drawing, forming part thereof.

The single figure is a perspective view of the playground device, showing my new design.

The dominant features of my new design are shown in solid lines in the drawing.

I claim:

The ornamental design for a playground device, substantially as shown and described.

ALEXANDER A. REICHER.
